(57) **CLAIM**

The ornamental design for a TV mount bracket, as shown and described.

DESCRIPTION

FIG. 1 is a front view of a TV mount bracket showing the new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top, and left side perspective view thereof; and,

FIG. 8 is a rear, top and right side perspective view thereof. The shade lines in the Figures show contour and not surface ornamentation.

1 Claim, 8 Drawing Sheets
